UNITED STATES PATENT OFFICE

163,586

COMBINED CALENDAR STAND AND DESK
RECEPTACLE UNIT

Otto Dingeldein, St. Louis, Mo., assignor to American Automobile Insurance Company, St. Louis, Mo., a corporation of Missouri

Application April 6, 1951, Serial No. 14,736

Term of patent 14 years

(Cl. D74--5)

To all whom it may concern:

Be it known that I, Otto Dingeldein, a German National, residing in the city of St. Louis and State of Missouri, have invented a new, original, and ornamental Design for a Combined Calendar Stand and Desk Receptacle Unit, of which the following is a specification, reference being had to the accompanying drawing, forming a part thereof.

In the drawing:

Fig. 1 is a front elevational view of a combined calendar stand and desk receptacle unit, showing my new design;

Fig. 2 is a top plan view;

Fig. 3 is a rear elevational view;

Fig. 4 is an end elevational view; and

Fig. 5 is a perspective view of the combined calendar stand and desk receptacle unit in a partially opened position.

The broken lines indicating a calendar as shown in Figs. 1 and 3 are merely representative of that which will appear thereon from month to month.

I claim:

The ornamental design for a combined calendar stand and desk receptacle unit, as shown and described.

OTTO DINGELDEIN.
